UNITED STATES PATENT OFFICE.

WILLIAM ALEXANDER LEITCH, OF SARLES, NORTH DAKOTA.

INTERNAL-COMBUSTION ENGINE.

1,334,619.

Specification of Letters Patent. Patented Mar. 23, 1920.

Application filed June 19, 1919. Serial No. 305,367.

To all whom it may concern:

Be it known that I, WILLIAM ALEXANDER LEITCH, a citizen of the United States, residing at Sarles, in the county of Cavalier and State of North Dakota, have invented certain new and useful Improvements in Internal-Combustion Engines; and I do declare the following to be a full, clear, and exact description of the invention, such as will enable others skilled in the art to which it app pertains to make and use the same.

My invention relates to improvements in internal combustion engines of the type in which two pistons slide one within the other in the cylinder, the gas being drawn into said cylinder, forced from the latter into the space between the two piston heads, compressed by the movement of such heads, and then fired to drive said pistons in opposite directions and impart both a pushing and pulling rotary action on the crank shaft.

One object of my invention is to generally improve and simplify engines of the above described type, and in carrying out this end, further objects are to provide a novel means for controlling the travel of the volatile gases to the cylinders and from the latter into the hollow piston.

With the foregoing in view, the invention resides in the novel construction and arrangements of parts hereinafter fully described and claimed, the descriptive matter being supplemented by the accompanying drawings.

Figure 1 is a side elevation of an engine constructed in accordance with my invention, parts being broken away and in section.

Figs. 2 and 3 are vertical transverse sections on the planes indicated by the lines 2-2 and 3-3 of Fig. 1.

Fig. 4 is a central vertical longitudinal section.

Fig. 5 is an enlarged section of one of the spark plugs and associated parts.

The engine may of course be constructed with any number of cylinders but for illustrative purposes I have disclosed two which are indicated in the drawings by the numerals 1, said cylinders preferably having water jackets 2 although other preferred cooling means could be employed. The cylinders 1 rise from an appropriate crank case 3 carrying bearings 4 for the crank shaft 5, and three cranks are provided on said shaft below each cylinder. Each set

of three cranks comprises two cranks 6 extending in the same direction from the center of the shaft, while the third crank 7 projects in the opposite direction. Connecting rods 8 rise from the cranks 6 and are pivoted to the lower end of hollow pistons 9 which slide within the cylinders 1, while other connecting rods 10 extend between the cranks 7 and pistons 11 which are slideable in the hollow pistons 9. The crank 7 of one set is opposed to the corresponding crank of the other set and consequently the action of the two cylinders will never be the same at any point throughout the revolution, thereby equalizing power and preventing vibration.

The engine is of the two-cycle type, in which the incoming gases discharge the exhaust gases into an exhaust manifold 12. Ports 13 lead to this manifold through the cylinder walls, and ports 14 in the hollow pistons 9 are adapted for registration with said ports 13 at the end of each power stroke as seen in Fig. 2, and simultaneously with this action, an intake port 15 in the piston 9, at a point opposite the exhaust port 14, communicates with a fuel passage 16 formed longitudinally of the cylinder. When this relation occurs, the piston 9 is at approximately the limit of its upward movement so that the gas previously drawn into the upper end of the cylinder is forced down the passage 16 and into the piston 9, serving to drive out the exhaust gases, in readiness for compression when the two pistons again move toward each other. A baffle 11 may be provided on each piston 11 in the same manner as the ordinary two-cycle engine, to drive the incoming gases up to the top of the piston 9, thereby thoroughly scavenging the latter of burnt gases. An intake manifold 17 discharges at its ends in the ports 16 and at its center is provided with a cylindrical valve casing 18 with one side of which a carbureter 19 communicates, and in said casing 18 is a rotary valve 20 driven by any preferred connections (not shown). It is the office of the valve 20 to place the manifold in communication with the carbureter on the intake strokes of the pistons 9 and to cut off such communication when said pistons ascend as seen in Fig. 2, thereby preventing escape of the gases drawn into the cylinder, with the result that they must be forced down the passages 16 into the hollow pistons 9 for compression. This

compression takes place when the two pistons 11 and 9 move toward each other as shown at the right hand end of Fig. 4. Ignition then takes place by a novel means described below so that the two pistons are driven in opposite directions to exert turning force on opposite sides of the crank shaft.

Briefly speaking, the ignition means consists of a spark plug formed of an inner section 25 and an outer section 26, carried respectively by the piston 9 and the cylinder 1, the arrangement being such as to bring the two sections of the plug in operative engagement when compression is complete, whereby the spark will be snapped between the electrodes 27 and 28 with which the inner section 25 is provided, and the compressed charge in the piston 9 is thus fired. The sections 25 and 26 are each provided with a metal shell 29 in contact with the parts carrying them, and since the ignition circuit is grounded on the engine in any preferred manner they will receive electrical energy therefrom. Within the shells 29, insulators 30 are secured by ring nuts or other preferred means 31, the insulator of the inner section 25 carrying the central electrode 27 while the insulator of the outer section is provided with an electrode 32. These electrodes 27 and 32 may be provided with spring contacts or the like 33 which are adapted to come into engagement as seen in Fig. 5 when compression is completed. Thus, when the ignition circuit is completed by the usual timer (not shown) the current will flow through the electrode 32, the contacts 33, and the electrode 27, will jump the gap between this electrode and the grounded electrode 28 and will return in the usual way through the engine base or the like.

From the foregoing, taken in connection with the accompanying drawings, it will be seen that I have provided an engine of extremely simple nature, yet one which will be highly efficient and reliable, and in every way desirable. Particular emphasis is laid upon the novel spark plug for firing the

charge in the hollow moving piston 9, and upon the rotary valve 20 for preventing return of gas through the manifold 17, thereby forcing such gas to travel through the passage 16 into the piston 9. These features constitute important advances in the art and excellent results are obtainable thereby.

Since probably the most advantageous details have been shown, they may well be followed, but within the scope of the invention as claimed, considerable latitude is allowed for making numerous minor changes.

I claim:

An internal combustion engine comprising a pair of parallel cylinders, a hollow piston in each cylinder, another piston in each hollow piston, cranks and connecting rods for moving the two pistons of each cylinder oppositely, a fuel passage extending along each cylinder and communicating with both the upper and lower ends thereof, an intake port in each hollow piston for registration with the lower end of said fuel passage when said piston reaches the limit of its upward movement and an intake manifold communicating at its ends with both fuel passages and having a cylindrical valve casing at its center, a carburetor communicating with said casing, a rotary valve in said casing for placing said carburetor in communication with the intake manifold when each hollow piston moves on its descending intake stroke, and for thereafter cutting off such communication, causing the ascent of the hollow piston to force the gas from the cylinder into said hollow piston by way of the fuel passage and intake port, means for exhausting the burnt gases from the hollow piston when the fresh gas is forced into them, and means for igniting the compressed gas when the two pistons move toward each other.

In testimony whereof I have hereunto set my hand.

WILLIAM ALEXANDER LEITCH.
